PRINTING PRESS INK FOUNTAIN

Curtis S. Crafts, Oak Park, Ill., assignor to Goss
Printing Press Company, Chicago, Ill., a corpo-
ration of Illinois

Application November 27, 1944, Serial No. 565,242

11 Claims. (Cl. 101—350)

1

The present invention pertains to ink fountains for printing presses, the general aim being to facilitate the removal of ink from such devices without either wastage of ink or loss of time.

Occasion frequently arises for removal of ink from printing press fountains either in cleaning the same, or more often, in changing from one color to another. In fixed fountains such removal has heretofore been effected by scooping the ink out of a fountain with a spatula or the like and sopping up the remainder with rags. Such a procedure is not only tedious and time-consuming, but very wasteful of the ink since a large portion of it cannot be reclaimed. The latter is a particularly important factor in the event that expensive heat setting inks or the like are employed, as is done for example in magazine presses.

To obviate the shortcomings of the prior practice outlined above, it is an object of the present invention to provide a fountain which is movably mounted in such manner that it may be readily swung from working position, in which it supplies ink to a coating fountain roller, into a tilted drainage position in which the ink spills out by free gravity flow over the lip or edge of the fountain for collection in a bucket or other suitable receptacle.

Another object is to provide a fountain equipped with an overshot fountain roller and embodying an arrangement for rocking the fountain between a working position in which the fountain is firmly locked in a precisely fixed upright position, and an alternatively available drainage position in which the fountain is tipped so that its contents run out in a free flowing stream.

In a somewhat more specific aspect, it is an object of the invention to provide a fountain having an overshot fountain roller and coating regulating blade, together with means for rocking the fountain and blade bodily as a unit about the axis of the fountain roller for discharging the contents of the fountain and without disturbing the adjusted setting of the blade with reference to the periphery of the roller.

Still another object is to provide a fountain of the character set forth above and in which a pickup roller coating with the fountain roller is mounted to rock with the fountain about the axis of the fountain roller and thus clear the rear side of the latter to facilitate cleaning.

Further objects and advantages of the invention will become apparent from the following description, taken in connection with the accompanying drawings in which:

2

Figure 1 is a perspective view of a printing press ink fountain embodying the present invention.

Fig. 2 is a view similar to Fig. 1 but showing the fountain tilted for discharge of the ink from it.

Fig. 3 is an enlarged transverse sectional view taken substantially along the line 3—3 in Fig. 1.

Fig. 4 is a fragmentary detail sectional view taken substantially along the line 4—4 in Fig. 3.

Fig. 5 is a transverse sectional view similar to Fig. 3 but showing the fountain in its tilted or discharge position.

Fig. 6 is an end elevation of the fountain.

15 While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

15 Referring more particularly to the exemplary embodiment of the invention illustrated in the accompanying drawings, an ink fountain or pan 10 has been shown and in which a conventional overshot fountain roller 11 is arranged to revolve. During use the fountain roller 11 runs partially submerged in a bath of ink whose level is indicated at 12 in Fig. 3. On the side of the roller 11 emerging from the ink bath a regulating blade 13 is provided and which presents an edge extending longitudinally of the roller. The displacement of the edge of the blade from the roller periphery is determinative of the thickness of ink film carried by the latter to a pickup roller 34, the usual adjusting means 14 serving to flex the blade at appropriate intervals along its length to control the thickness of the ink film. From the pickup roller the ink passes over a succession of rollers or the like (not shown) to a suitable printing cylinder or plate, the specific mechanisms used depending upon the type of press in which the fountain is employed.

As so far described, the arrangement is more or less conventional and removal of ink from the fountain would entail the tedious and wasteful process of scooping it out with a spatula and soaking it up with rags. To overcome that difficulty, the fountain 10 herein has been pivoted to tilt laterally about the axis of the fountain roller 11 so that when tilted its contents will pour out in a free flowing stream even though

it be highly viscous. For that purpose the fountain 10 is journaled to swing on a pair of bushings 15, one of which appears in Figs. 4 and 6, and through which passes the shaft 16 of the fountain roller 11. Such bushings 15 are clamped by split blocks 17 on supporting brackets 18 carried by the press frame fragmentarily indicated at 19. Sleeve bearings 20 telescoped within interior bores 21 in the bushings 15 journal the fountain roller shaft 11, while reduced end portions 22 on the bushings 15 pass through apertures 23 in the end plates or members 24 of the fountain 10 to journal the latter coaxially with the fountain roller.

Swinging of the fountain 10 is accomplished by means of a manual actuating mechanism (Figs. 1, 3 and 4) including a worm 25 journaled in projections 26 on the bracket 27 and having a squared end 28 to which a suitable wrench or operating crank (not shown) may be applied. The worm 25 meshes with a worm wheel 29 fixed to a transverse shaft 30 journaled in the brackets 27 at opposite ends of the fountain, such shaft having rigid therewith crank arms 31. Pivoted to the outer end of such crank is a link 32 which is in turn pivoted to a lug 33 on the lower front side of the fountain. As the worm 25 is revolved to swing the crank arm 31 counterclockwise (as viewed in Fig. 3), the fountain 10 is tilted downward to the discharge position of Figs. 2 and 5. Similarly, turning of the worm in the opposite direction restores the fountain to its upright or working position of Figs. 1 and 3.

Precision location of the fountain 10 in its working position is important for a number of reasons including the fact that the pickup roller 34 is arranged to swing with it and must therefore be restored to exactly the proper position for contact with the next roller in the series (indicated at 35 in Fig. 3) to which the ink is transferred. To effect such precision location of the fountain when in working position a positive stop arrangement is provided including a lug 36 rigid with the bracket 18 (Fig. 4) and presenting an accurately machined top surface 37 against which a complementary machined surface 38 on the lower side of the fountain abuts when the fountain is in working position. Once the stop surfaces 37, 38 have been abutted, the fountain is securely locked in such position by the action of the worm 29 which is preferably of the low efficiency or so-called non-reversible type, meaning that it cannot be revolved by turning of the worm wheel.

The fountain 10 is preferably of the special shape shown, both in order to facilitate drainage of ink from it and to aid in efficiently supplying ink to the fountain roller 11 when in use. In the particular construction shown the fountain 10 comprises not only the end plates heretofore mentioned but also a casting or body member 39 to which such end plates are bolted and which is shaped to provide a flat bottom wall 40 (Fig. 3) as well as flat divergent side walls 41 and 42, giving the fountain body a tapered cross section. The rear side wall 41, away from which the fountain roller rotates in carrying ink toward the blade 13, is fairly steeply inclined so that ink will be crowded by it toward the roller and thus carried under the latter. The opposite or front side wall 42 is, on the other hand, less steeply inclined, thereby minimizing the angle through which the fountain must be tilted in order to effect complete gravity drainage of its contents.

A heat exchange jacket is provided on the ex-

terior of the fountain 10 to accommodate either the heating or cooling, as the case may be, of certain types of inks that should be kept at particular temperatures while in use in the fountain. Such jacket in the present instance comprises a chamber 43 bordered by a rectangular wall member 44 integral with the fountain body 39 and closed by a bottom plate 45. Water or other suitable heating or cooling medium enters at the inlet 46 and leaves the chamber 43 at the outlet 47. To accommodate the use of such a fluid-supplied jacket even with a tiltable fountain such as that shown, flexible conduits or hoses 48 leading to the inlet and outlet 46, 47 are provided (Figs. 3 and 5). Maintenance of the fluid connections during emptying of the fountain is desirable in that lowering of the ink viscosity through application of heat may be, at times important in effecting complete and rapid drainage.

In the illustrated construction both the regulating blade 13 and the pickup roller 34 are arranged to move bodily, and as a unit, with the fountain 10 in the course of the latter's tilting. Such unified motion of the blade, transfer roller and fountain is made possible by the fact that their common axis of tilting motion is coincident with the axis of the fountain roller 11. Upon reference to Fig. 3 it will be observed that the fountain, blade and pickup roller are, in a general sense, located at circumferentially spaced points about the periphery of the fountain roller. In the particular construction illustrated, the regulating blade 13 is fixed to the underside of an elongated housing or support 49 extending lengthwise of the fountain and secured at its opposite ends to the end members 24 of the fountain. A retaining strip 50 clamps the portion of the blade 13 remote from the fountain roller 11 to the housing 49, leaving the opposite edge portion of the blade free for flexure toward and away from the fountain roller. The usual regulating screws 51, threaded in the housing 49, project into contact with the upper face of the blade and serve to vary its flexure. Such screws are located at suitable intervals along the length of the blade as, for example, one for each columnar width on the press. The open top portion of the fountain 10 between its front edge or lip 52 and the blade supporting housing 49 is closed by a removable sheet metal cover 53. The pickup roller, on the other hand, is journaled in brackets 54 bolted to the end portions of the housing 49.

The operation of the disclosed apparatus will, in general, be clear from the foregoing. By way of brief recapitulation, it may be observed that during press operation the fountain 10 is in the generally upright or working position shown in Figs. 1 and 3. In such case the stop faces 37, 38 are abutted in firm engagement with each other so that the fountain 10 is located with precision in its working position as heretofore described. The fountain roller revolves counterclockwise (as viewed in Fig. 3) picking up a peripheral film of ink from the bath in the fountain, and the thickness of such film is regulated by the setting of the blade 13. The regulated film of ink passing under the blade 13 progresses to the pickup roller 34 to which it is transferred and from which it passes on to the point of use in the press as heretofore described.

To empty the fountain 10 and clean it during idle periods for the press, the operator removes the cover 52, applies a drainage guard 54 (Fig. 2)

and then turns the worm 25 to tilt the fountain downward into the drainage position of Figs. 2 and 5. The guard 54 is simply a strip of sheet metal fixed to the front edge or lip of the fountain by suitable clamping screws (not shown) and which is suitably shaped as indicated at 55 to form a spout-like discharge opening for the ink so that it may run out into a bucket or the like (not shown). As indicated in Fig. 5, the front wall 42 of the fountain is in approximately horizontal position when the fountain is canted for drainage, that degree of tilt usually being adequate for free flowing spillage of the ink. When the fountain is in such tilted position the operator has free access (through the space previously occupied by the cover 52) to the interior of the fountain for wiping out any sludge or remnants of ink that may remain. Since the pickup roller 34 is tilted forward he also can reach the rear side of the fountain roller to wipe it clean. It will thus be seen that the ink can be readily and quickly drained from the fountain, making possible maximum reclamation of the ink and thorough cleaning of the fountain structure.

In restoring the fountain to operating position the operator simply revolves the worm to swing the fountain, pickup roller and blade back to working position. During all such rocking or tilting motion the displacement of the blade with reference to the fountain roller remains undisturbed so that no readjustment of the blade by the regulating screws 51 is required following drainage of the fountain.

I claim as my invention:

1. The combination of a printing press ink fountain, an overshot fountain roller, means journaling said roller for rotation within said fountain, a regulating blade, means supporting said regulating blade with a free edge of the same adjacent the periphery of the roller and extending longitudinally of the latter, and means supporting said fountain and blade for coincident rocking motion about the axis of said roller between an upright operating position for said fountain and a tilted drainage position therefor.

2. The combination of a printing press ink fountain, an overshot fountain roller, means journaling said roller for rotation within said fountain, a regulating blade rigidly mounted on said fountain and adapted to coact with said fountain roller, and means supporting said fountain for rocking motion about the axis of said roller between a working position and an alternatively available drainage position.

3. The combination of a printing press ink fountain of generally trough shape, means for journaling an overshot fountain roller to rotate in said fountain, a pickup roller adjacent the upper side of said fountain roller, and means supporting said fountain as well as said pickup roller for rocking as a unit about the longitudinal axis of said fountain roller between an upright operating position for said fountain and a tilted drainage position therefor.

4. The combination of a revolute overshot fountain roller fixed on a shaft projecting axially from opposite ends thereof; a pan-shaped ink fountain, a regulating blade and a pickup roller all located at circumferentially spaced points about the periphery of said fountain roller for coaction therewith; means journaled on said shaft supporting said fountain, blade and pickup roller for oscillatory motion in unison with each other about the axis of said fountain roller be-

tween an operating position in which said fountain is generally upright for presentation of a contained body of ink to said fountain roller and a drainage position in which said fountain is canted for free spillage of its contents.

5. The combination with an ink fountain having a fountain roller revolute therein and a regulating blade rigidly mounted on said fountain for coaction with said roller, of means supporting said fountain for tilting movement between two alternatively available positions one of which is an operating position in which said fountain is located to present a body of ink to said roller and the other of which is a drainage position in which said fountain is canted for free spillage of its contents.

6. The combination of an ink fountain having a fountain roller revolute therein, means supporting said fountain for movement between alternatively available positions one of which is an operating position in which said fountain is located to present a body of ink to said roller and the other of which is a drainage position in which said fountain is canted for free spillage of its contents, means entirely supported by said fountain for picking up ink from said roller, said fountain presenting an accurately located stop surface, and a coacting stationary stop located to abut against said stop surface when said fountain is in said operating position to thereby effect precision location of said fountain in the latter position.

7. The combination of an ink fountain having a fountain roller revolute therein, means supporting said fountain for movement between alternatively available positions one of which is an operating position in which said fountain is located to present a body of ink to said roller and the other of which is a drainage position in which said fountain is canted for free spillage of its contents, ink transfer means entirely supported by said fountain for picking up ink from said roller, said fountain presenting an accurately located stop surface, a coacting stationary stop located to abut against said stop surface when said fountain is in said operating position to thereby effect precision location of said fountain in the latter position, and means for locking said fountain in operating position with said stationary stop in engagement with said stop surface.

8. The combination of an ink fountain having a fountain roller revolute therein, means supporting said fountain for movement between alternatively available positions one of which is an operating position in which said fountain is located to present a body of ink to said roller and the other of which is a drainage position in which said fountain is canted for free spillage of its contents, a pickup roller adapted to coact with said fountain roller and mounted on said fountain for bodily movement therewith, said fountain presenting an accurately located stop surface, a coacting stationary stop located to abut against said stop surface when said fountain is in said operating position to thereby effect precision location of said fountain in the latter position, and an operating mechanism for tilting said fountain including a manually rotatable worm meshing with a worm wheel, said worm being of the low efficiency type wherefore said fountain is held against inadvertent displacement whenever said fountain is at rest.

9. The combination of an ink fountain having a fountain roller revolute therein, means sup-

porting said fountain for movement between alternatively available positions one of which is an operating position in which said fountain is located to present a body of ink to said roller and the other of which is a drainage position in which said fountain is canted for free spillage of its contents, a pickup roller adapted to coact with said fountain roller and mounted on said fountain for bodily movement therewith, said fountain presenting an accurately located stop surface, a coacting stationary stop located to abut against said stop surface when said fountain is in said operating position to thereby effect precision location of said fountain in the latter position, an operating shaft extending longitudinally of said fountain and located generally beneath the same, a plurality of crank arms rigid with said shaft and projecting laterally therefrom at spaced points, connecting links pivoted respectively to said fountain and to the outer ends of said crank arms, and means including a manually rotatable low efficiency worm meshing with a worm wheel for rotating said shaft to thereby tilt said fountain.

10. The combination of an ink fountain having an overshot fountain roller revoluble therein, means supporting said fountain for lateral tilting motion about the axis of said fountain roller between alternatively available operating and drainage positions in which said fountain is respectively in generally upright position and in canted position for free spillage of its contents, a regulating blade and a pickup roller each adapted to coact with said fountain roller and bodily movable with said fountain about the axis of said fountain roller, said fountain presenting an accurately located stop surface, and a coacting stationary stop located to abut against said stop surface when said fountain is in said operating position to thereby effect precision location of said fountain in the latter position.

25

11. The combination of an ink fountain having an overshot fountain roller revoluble therein, means supporting said fountain for lateral tilting motion about the axis of said fountain roller between alternatively available operating and drainage positions in which said fountain is respectively in generally upright position and in canted position for free spillage of its contents, a pickup roller adapted to coact with said fountain roller, means for journaling said pickup roller on said fountain for bodily movement with the latter about the axis of said fountain roller in the course of rocking of said fountain, said fountain presenting an accurately located stop surface, and a coacting stationary stop located to abut against said stop surface when said fountain is in said operating position to thereby effect precision location of said fountain in the latter position.
